UNITED STATES PATENT OFFICE

ARTHUR WELSH AND GEORGE RAW, OF NEW WASHINGTON, ENGLAND

APPARATUS FOR CONVEYING FROM THE WORKING FACE IN MINES

Application filed August 13, 1928, Serial No. 299,349, and in Great Britain August 15, 1927.

This invention comprises improvements in or relating to apparatus for conveying from the working face in mines and is particularly concerned with conveyors of the kind in which the cars or tubs are drawn in a train from the coal face on to a bridge in a heading, cutting or roadway and there emptied of their contents, into cars or trucks beneath or within the bridge, by sliding displacement of the bottoms of the tubs by the haulage gear after automatic release thereof. 55

According to the present invention, slideable bottom plates of a train of cars or tubs are flexibly connected with one another by 60 rectangular open-frame couplings connected by vertical pivots at each end with the respective bottom plates. It is also of advantage to arrange for the trains automatically to change over the points of their respective

track branches in passing to the bridge so as to set the points for the return of the trains to the same track branches after emptying as will be hereinafter described. 65

In order to enable the invention to be readily understood reference is directed to the accompanying drawings, illustrating a suitable construction of mine conveyor in accordance with these improvements, and in which:— 70

Figure 1 is a plan of part of a mine working showing the position of the bridge or loading station relatively to the coal face and trains at the coal face. 75

Figure 2 is an elevation of the heading seen in Figure 1. 75

Figure 3 is a side elevation to a larger scale of a portion of the loader or bridge with part of a train thereon. 80

Figure 4 is a detached plan view, to a larger scale than Figure 3, of the bottom of the first car of a train and part of the bottom of the second car, with coupling between them. 85

Figure 5 is a side elevation of Figure 4. 85

Figure 6 is an end elevation of one of the cars or tubs on a larger scale than Figure 3. 85

Figure 7 shows in elevation on a still larger scale, the releasable catch device for the slideable bottoms of the cars. 90

Figure 8 is a side elevation of a coupling for the cars or tubs. 90

Figure 9 is a plan of Figure 8 with the securing nuts omitted, and 95

Figure 10 is a view illustrating the stop devices for arresting the cars against reverse movement until their bottoms have been replaced after unloading. 95

In Figures 1 and 2, A indicates a heading or cutting, B a coal face extending on either side of the heading, C the ordinary mine 100

50 The haulage gear may be of any suitable

track in the heading A, and D the conveyor track comprising branches running along the working in front of the coal face B. The conveyor illustrated comprises two trains E of cars or tubs and there is an iron frame-work 5 F constituting a bridge or loader and a suitable haulage mechanism hereinafter described of a horse-power dependent upon the size and number of tubs required on each train. The two-way turn G of the conveyor 10 track is shown in direct line with the loading station at F. It connects the right and left hand branches of the track with a common branch passing to the bridge and enables one 15 train of tubs or cars to be loaded while the other train is being emptied. C' shows a swerve of the ordinary mine track C which passes through an opening F' in the bridge to allow large cars or tubs (not shown) to 20 pass either to the bridge for loading or from the bridge after loading. These large tubs stand inside or beneath the bridge to be filled and the trains E are drawn on to the top of the bridge for discharge of their contents into 25 the larger cars or tubs beneath as will be described. The points or switch G' at the double turn G are adapted to be changed over automatically by each loaded train as it comes 30 out to the loading station F to be emptied so that the points will be set ready for the return of the train to the same track branch and thus to the same side of the coal face B after emptying. The points may, for example, be freely pivoted and moved by the tub wheels 35 as they pass out to the loading station as will be readily understood.

The haulage gear suitably consists of a hauling engine mounted on the bridge or loader F at the point H. The engine itself 40 is not shown in the drawings as its only characteristic feature is that it comprises three winding drums which are shown diagrammatically at a, a', a''. These drums are mounted on a single shaft and controlled by 45 clutches and levers in any suitable or known manner which will be understood by those skilled in the art without illustration. The middle drum a carries a main rope c which is used for drawing the loaded trains from the coal face to the loading station F and also 50 withdraws the sliding bottoms of the tubs as will be described. The left- and right-hand drums a', a'' carry tail ropes c', c'' which draw the sliding bottoms back and take the empty 55 trains back from the bridge to the coal face. The tail ropes c', c'' are attached to the rear tub of the respective trains and are not detached therefrom. The main rope c is detached from a train when the latter reaches 60 the required position on its return to the coal face and is then attached to the other train to enable that to be taken to the bridge for emptying. The haulage ropes pass over suitable drums, wheels or rollers j at suitable 65 points of the track for guiding purposes.

In Figure 3, conveyor tubs or cars of a train are seen at b on the bridge F and the winding drum or drums of the haulage engine are represented by a, a', a''. The bottoms of the cars are in the form of separate plates d connected together by couplings e and slidably mounted in guides f, Figures 3 and 6, in the frame or sides of the tubs b. From Figures 4 and 5 it will be seen that the bottoms d are of substantially rectangular form and that the couplings e, consist of an open rectangular frame constituted by transverse end members g of shallow U form joined by longitudinal side links h. The latter are pivotally secured in double eyes k of the end members g by means of horizontal cotter bolts l and the end members have central pivotal connection with the bottom plates d by vertical cotter bolts at m. The members g as shown are slipped in between the under surface of the bottom plates and brackets d' thereon. The rectangular opening in the couplings e is for discharge of coal and it is made as nearly as possible as wide as the bottoms of the tubs and about as long as the distance between adjacent bottom plates, so that it presents a large unobstructed opening as the bottoms slide forward on the emptying of the cars as hereinafter described. The transverse members g of the couplings e are set down or cranked at each end as at i to allow them to pass beneath the guides f when drawing the bottoms of the tubs, and ball races such as f' may be fitted along the edges of the sliding bottoms to facilitate their movement in the guides.

By reference to Figure 3 it will be seen that on the forward wall of the first of the tubs of the train, a rod n is mounted to slide vertically in suitable brackets o, p. This rod normally locks the bottom plates d of the car against sliding movement but can be released by a forwardly extending striker lever q as will be described. As shown also by Figure 7, the lever q is a bent two-armed lever pivotally mounted at r in the bracket o. It has connection by pin s and slot t at its rear end, with the upper end of the rod n, upon which a helical spring u is placed, between the bracket o and a collar v adjustably mounted on the rod, for normally maintaining the lower end of the rod n in engagement with a hole or slot w in the forward end of the bottom plate d of the first car, see also Figure 4. The forwardly extending free or striker end of the lever q is directed downwardly and lies in the path of a stop x on the bridge (Figure 3) and when it engages such stop the locking rod n is released from the holes w against the action of the spring u whereupon the bottom plates can slide forwardly as will be described. Adjustment of the position of the outer end of the lever q to suit requirements is possible by altering the position of the collar v on the locking 130

rod by means of the screw v' . The bottom plate may be reinforced about the hole w by plates y if desired and to facilitate the re-engagement of the locking rod with the hole when the bottom plates are replaced the upper one of the plates y may be recessed as shown at y' in Figure 4. Obviously arrangement may be made for the use of more than one such locking rod, if required.

In order to effect the forward sliding movement of the bottom plates of the cars, the main haulage cable c leading from the winding drum a is attached to a haulage connection device such as a shackle and hook z at the forward end of the bottom plate of the first tub, see Figures 3 to 5. This bottom plate has a shallow V slot 1 for attachment of the shackle and hook by the pivot 2. Preferably the plate is reinforced about the slot by the plate 1^a . The pivot pin 2 may be fitted with a roller 2^a and it will be seen that the slot 1 readily allows of slight movement of the shackle to either side if the cars are turning a bend, while retaining the shackle centrally on straight parts of the track C. A similar connection for the tail cable c' or c^2 may also be used at the rear end of the bottom plate of the last tub as will be understood without further illustration. The couplings e between the bottom plates of the various tubs of the train allow of any desired flexibility in the train of plates.

The couplings between the tubs themselves suitable take the form shown in Figures 3, 8 and 9. This comprises end members 3, 4 with vertical pivot parts 5, 6 respectively for engaging holes or slots in brackets 7 on the tub bodies or frames, and a horizontal bar 8 hingedly connected between the end parts 3, 4 by horizontal pivots. One swivel member 3 is straight with a double eye at one end within which the horizontal bar 8 is secured by rivet 8^a to form a hinge. The part 4 is in the form of an L with a double eye formed at the end of the foot for attachment of the other end of the horizontal bar 8 by a cotter bolt 9, this arrangement being convenient for coupling and uncoupling the bodies of the tubs when required. The pivots 5, 6 terminate at the extreme upper end in threaded parts for application of nuts 10 for securing the couplings in the tub brackets 7. These couplings, as will be understood, will maintain the desired distance between the tubs while allowing of flexibility in rounding curves and the slight flexibility required to accommodate to unevennesses of the track.

For arresting the trains of tubs when hauled from the working face, stops such as 11 are provided on the bridge F. These stops are conveniently formed by the downwardly bent terminal parts of runners 12 arranged along each side of the track D, on the bridge and into which the tub wheels b' run as the

tubs come on to the bridge. The forward wheels of the first tub engage the stops, which are advantageously reinforced by triangular brackets or gussets 13. Immediately beneath the stop brackets 13 other brackets such as 14 are arranged on the framework of the bridge on each side of the track to support stop devices for preventing rearward movement of the tubs until the desired time. These stop devices suitably consist of two-armed levers 15 (Figures 3 and 10) mounted in the brackets 14 and provided with upwardly projecting stops 16 on the rear arms and rolls 17 at the ends of the forward arms which incline upwardly and forwardly. Normally, the rolls on the levers lie in the path of sliding movement of the bottom plates d of the tubs and the stops 16 below the level of the track surface to the rear of the front wheels of the first tub as shown by Figure 3. Part of the roll and lever is broken away in Figure 3 to illustrate parts behind.

For receiving and supporting the bottom plate of the first tub, and preventing it from lifting when it is drawn out, guides 19 may be mounted on the bridge F, Figure 3, and stops 20 are provided to determine the amount of forward movement. Movement of the bottom plates into their guides f and 19 is facilitated by lip formations 21 thereof shown in Figure 3.

In operation, the main haulage rope c is attached to the hook z of a filled train and the hauling engine started to draw this train to the bridge F by operation of the central drum a . As the train passes round the bend at G (Figure 1), its wheels automatically switch over the points at G' and the train passes thence to the bridge for unloading. On reaching the bridge the wheels of the tubs pass into the runners 12 (Figure 3) and the train will come to a standstill when the front wheels of the first tub engage the stops 11. Just at this time, the striker lever g of the locking rod n on the first tub will also meet its stop z and lift the locking rod against the action of the spring u to release the bottom plates of the tubs. The latter will then be hauled forward by the haulage gear until brought to a standstill by the stops 20 in the guides 19. These stops may suitably arrest the plates when they have moved forward a distance about equal to the length of a car or tub and it will be seen that while the plate of the first tub enters the guides 19, plates to the rear of this one enter the guides f of the respective cars in front. As the bottom plates d slide forward, the first plate engages the rolls 17 on the levers 15 and thus the retaining stops 16 are moved upwardly into the path of the front wheels of that tub, this position being seen in Figure 10. Further, as the bottom plates of the tubs slide along, the couplings e between the plates will pass beneath the respective tubs in front and

the coal in the tubs will discharge through the rectangular openings in these coupling members and into large tubs or trucks which would be within the bridge. The openings in the coupling members, being unobstructed, allow ready discharge of coal which takes place from each tub from the rear forwardly. After discharge of the tubs, the haulage drum a' or a^2 , as the case may be, is set going in reverse direction to the manner in which the drum a was operated, so as to wind in the tail rope c' or c^2 and return the empty train to the coal face. As soon as the reverse winding starts, the bottom plates d of the tubs of the train begin to return to their original position, but movement of the tubs is, as yet, prevented by the stops 16. However, immediately the bottom of the first tub is past the rolls 17, the stops 16 drop clear of the wheels of that tub and allow the train to move backwards, the plate of the last car having come against a stop. By now the hole or slot w in the foremost bottom plate is in position again to receive the locking rod n . Therefore, when the backward movement commences, the lever q is released and the spring u presses the locking rod into the hole or slot w . The train of cars is then drawn back again to the coal face for reloading and as the train, in passing to the bridge, switches over the points at G' , the train will return to the same side of the coal face as it came from. The other train now loaded, can be drawn to the bridge for emptying, by shifting the main haulage rope c to that train and repeating the operations above described, and so on, each train in turn setting the points at G' for return of the trains to their appropriate sides of the coal face as will be readily understood. In all the movements of the cars or tubs the couplings aforesaid give the required flexibility and it will be seen that they comprise no loosely hanging parts likely to foul the track or other fixtures or to interfere with the sliding of the bottom plates.

We claim:—

1. Mine conveyor comprising a train of tubs with slidable bottom plates, rectangular open-frame couplings secured by vertical pivots at each end to respective bottom plates, and means on the train of tubs co-operative with means at a bridge in the mine for releasing said bottom plates when the train reaches the bridge.
2. Mine conveyor comprising a train of tubs with slidable bottom plates, rectangular open-frame couplings for the bottom plates comprising separate side and end members connected by horizontal pivots at the joints between them and the end members being secured by vertical pivots with respective bottom plates, and means on the train of tubs co-operative with means at a bridge in the mine for releasing said bottom plates when the train reaches the bridge.

3. Mine conveyor comprising a train of tubs with slidable bottom plates, rectangular open-frame couplings secured by vertical pivots at each end to respective bottom plates and set down at the sides to clear guides on the tubs for the plates, and means on the train of tubs co-operative with means at a bridge in the mine for releasing said bottom plates when the train reaches the bridge. 70

4. Mine conveyor comprising a train of tubs with slidable bottom plates, means for coupling said plates together, a catch device on the first tub for locking the bottom plates against sliding movement, and a forwardly extending striker lever connected with said catch device and co-operative with means at a bridge in the mine for releasing such catch and allowing the bottom plates to slide when the train of tubs reaches the bridge. 75

5. Mine conveyor comprising a train of tubs with slidable bottom plates, means for coupling said plates together, a catch device on the first tub for locking the bottom plates against sliding movement, a forwardly and downwardly extending striker lever connected with said catch, a bridge in the mine where the tubs are emptied and a stop on the bridge disposed in the path of said striker lever substantially as and for the purpose set forth. 80

6. Mine conveyor comprising a train of tubs with slidable bottom plates, means for coupling said plates together, a yieldable catch bolt on the first tub for locking the bottom plates against sliding movement, a forwardly extending striker lever connected with said bolt and co-operative with means at a bridge in the mine for releasing such bolt and allowing the bottom plates to slide when the train of tubs reaches the bridge, and a collar adjustable on the catch bolt for adjustable setting of the striker lever substantially as and for the purpose set forth. 95

7. Mine conveyor comprising a series of tubs with slidable bottom plates, couplings for said tubs comprising end members vertically pivoted to the tubs and an intermediate bar member hinged horizontally to the end members, couplings for said bottom plates and means on one of the tubs co-operative with means at a bridge in the mine for releasing said bottom plates when the train of tubs reaches the bridge substantially as set forth. 100

8. Mine conveyor in accordance with claim 7, in which one of the end members of the tub couplings is of L form and the bar member is pivotally connected to such end member at the end of the foot of the L part substantially as and for the purpose set forth. 115

9. Mine conveyor comprising a train of tubs with slidable bottom plates, means for coupling said plates together, means on the train of tubs co-operative with means at a bridge in the mine for releasing said bottom 120 plates substantially as and for the purpose set forth. 125

plates to empty the tubs when the train reaches the bridge and a stop operated by the bottom plates in sliding for the purpose of holding the train against return movement after discharging until the bottom plates

5 have been replaced substantially as set forth.

10. Mine conveyor comprising a train of tubs with slidable bottom plates, means for coupling said plates together, haulage gear having the haulage rope connected with the bottom plates by V slot in the latter and means on the train of tubs co-operative with means at a bridge in the mine for releasing said bottom plates when the train reaches the bridge so that they are drawn forward

15 by the haulage gear substantially as set forth.

11. Mine conveyor comprising a train of tubs with slidable bottom plates, means for coupling the bottom plates together, haulage gear connectible with such plates, means on the train of tubs co-operative with means at a bridge in the mine for releasing said bottom plates when the train reaches the bridge so that they are drawn forward by the haulage gear, and guides on the bridge for receiving the bottom plate of the first tub of the train when the bottom plates are so drawn forward substantially as set forth.

12. A mine conveyor arrangement comprising in combination a plurality of trains of tubs, with slidable bottom plates, rectangular open-frame couplings for connecting the bottom plates together in respective trains, a bridge in the mine, haulage gear mounted on the bridge, a stop for arresting the trains on the bridge, a catch bolt on the first tub of each train for locking the bottom plates of that train, a downwardly and forwardly extending striker lever connected with said catch bolt, a second stop on the bridge for engaging said striker lever when the trains are drawn on to the bridge against the first-mentioned stop, thus releasing said bottom plates so that they are drawn forward by the haulage gear, means on the bridge, and operated by said plates as they move forward, for holding the trains against return movement from the bridge, until such bottom plates are replaced, and conveyor track comprising branches of which the points are adapted to be switched over by the respective trains in passing to the bridge substantially as hereinbefore set forth.

13. A mine conveyor arrangement comprising in combination a plurality of trains of tubs with slidable bottom plates, means for coupling the bottom plates together in respective trains, conveyor track comprising a plurality of branches for the separate trains, a bridge in the mine, main haulage and individual tail ropes for the trains, a hauling engine mounted on said bridge and comprising a winding drum for main haulage and individual winding drums for the respective tail ropes, a catch device on the

first tub of each train for locking the bottom plates of that train, a striker lever connected with said catch device, and a stop at the bridge for engaging said striker lever when the trains are drawn on to the bridge thus releasing said bottom plates so that they are drawn forward by the main haulage, said catch device re-locking the bottom plates when the latter are drawn reversely by the respective tailing rope and winding drum prior to return of the trains from said bridge substantially as set forth.

14. A mine conveyor arrangement comprising in combination a plurality of trains of tubs with slidable bottom plates, means for coupling the bottom plates together in respective trains, a bridge in the mine, haulage gear mounted on the bridge, a catch device on the first tub of each train for locking the bottom plates of that train, a striker lever connected with said catch device, a stop at the bridge for engaging said striker lever when the trains are drawn on to the bridge, thus releasing said bottom plates so that they are drawn forward by the haulage gear, and conveyor track comprising branches of which the points are adapted to be switched over by the respective trains in passing to the bridge substantially as set forth.
